SEARCHLIGHT CONTROLLER

John F. Peters, Edgewood, Pa., assignor to Westinghouse Electric & Manufacturing Company, East Pittsburgh, Pa., a corporation of Pennsylvania

Application August 31, 1935, Serial No. 38,769

15 Claims. (Cl. 240—1.2)

My invention relates, generally, to remote control apparatus and systems, and, more particularly, to a remote control station or comparator, as is commonly termed, for use in connection with movable objects, such as searchlights, guns and the like which are to be moved either manually or automatically in accordance with the movements of some other object or at will or in some other manner.

In the operation of searchlights for example, for anti-aircraft defense, it is the usual practice to manually control the movements of the light in azimuth and elevation by means of a suitable remote control system from a remote station to which station data is transmitted from a listening station in the manner disclosed by my copending application Serial No. 21,010, filed May 11, 1935, now Patent No. 2,130,899 of September 20, 1938. By the use of separate azimuth and elevation controls for the searchlight, its position relative to the position of the sound locator may be maintained by the operator or operators at the remote or comparator station. Thus the searchlight may be caused to follow the movements of an object even though the object cannot be seen and the searchlight is not in operation in order that when the light is set in operation its beam will be on or very near the object.

It is desirable, however, to also provide for directing a telescope, binocular or other sighting device upon the object to be illuminated in order that the operators at the remote control or comparator station may readily view the object when the light is started. The telescope, etc., to be fully effective must be so actuated or controlled that its movements will correspond to the movements of the light as it is adjusted from the comparator station.

In addition to the manual control of the position of the light and the corresponding operation of the binocular or telescope, in accordance with the operation of a sound locator, it is desirable to provide for causing both the light and binocular to be moved in such manner that the beam projected by the light covers or traverses some predetermined path during a cycle of operation. This operation is known as a searching or scanning operation and is resorted to in order to quickly locate the object if it is not within the beam when the light comes on. In this instance also, it is important that the movements of the light and binoculars be so co-ordinated that any object picked up by the beam may be instantly observed by the operator.

Accordingly, the object of my invention, generally stated, is to provide a remote control station or comparator unit which shall be simple, accurate and effective in operation, which may be economically manufactured and readily utilized.

A more specific object of my invention is to provide for automatically controlling the movements of a binocular or sighting device located at the comparator station in accordance with the movements of the searchlight.

Another object of my invention is to provide a remote control or comparator device which may be operated manually to separately control the azimuth and elevation movements of a searchlight at will, and manually or by power to effect a predetermined co-ordination of these movements to cause the projected beam to travel in a path of predetermined shape to effect searching operations.

A further object of my invention is to provide in a remote control system for a searchlight for causing the beam to be moved over a path in the shape of a closed spiral in response to the operation of a single operating device.

A still further object of the invention is to provide in a comparator unit having a pivotally mounted apparatus casing and a binocular mounting thereon, for automatically moving the casing in accordance with the movements in azimuth of the searchlight and the binocular mounting in accordance with the movements in elevation of the searchlight when these movements are separately performed and for automatically moving the binocular mounting in accordance with both the azimuth and elevation movements of the searchlight when these movements are jointly performed in a co-ordinated manner.

Another object of the invention is to provide a mechanism for effecting co-ordinated movements of the azimuth and elevation position control transmitters in a comparator unit which may be actuated manually or by motor and which shall function automatically to cause the object controlled by the transmitters to move in a predetermined manner in cycles.

An additional object of the invention is to provide an actuating mechanism for the position controlling transmitters in a comparator unit having a binocular mounting which may be actuated manually or by power means and which functions to simultaneously actuate the transmitters and binocular mounting in accordance with a predetermined cycle of co-ordinated movement.

Another object of the invention is to provide

a comparator control unit of light weight but sturdy construction, which is flexible and accurate in operation and of such nature as to facilitate to the highest degree the control of a searchlight or other object in accordance with the movements of a directing device in the nature of a sound locator or the like.

These and other objects of the invention will become apparent from a reading of the following detailed description in connection with the drawings, in which:

Fig. 2 is a detailed perspective view of the mechanism of the comparator unit;

Figs. 3 and 4 are views partly in elevation and partly in section of the comparator showing details and arrangement of the mechanism.

Fig. 5 is a view in elevation of the searcher mechanism;

Fig. 14 is a view, partly in section and partly in elevation, of a portion of the binocular mount; and

Fig. 15 is a diagrammatic view of a remote control system showing the application of the comparator.

In practicing my invention, the comparator controller which comprises generally a casing for housing the transmitters, actuating mechanism, etc., is rotatably mounted on a suitable tripod support. The position transmitters in the casing may be individually operated by manual means at different speeds or they may be collectively actuated by a searcher or scanning mechanism which produces a predetermined co-ordinated cycle of movements of the transmitters such as to cause the controlled object, such for example as a searchlight, to be moved in such manner as to cause the light beam to systematically scan a predetermined area in the sky about a predicted position of an airplane or the like.

The searcher mechanism may be operated by a motor or by hand, or both, so that one actuating medium may be used to modify the action of the other. Likewise, the operation of either one of the transmitters while being actuated by the search mechanism may be modified by their respective manual operating means.

In order to limit the speeds at which the transmitters may be operated by their manual means provision is made for causing the manual means to become temporarily ineffective when the speed of the transmitter exceeds a predetermined value.

The comparator controller includes a device for supporting a sighting means, such for example, as a telescope or binocular in such posi-

tion that the operator may view the object upon which the searchlight beam is directed. The supporting means is rotatably supported by the casing in order to move the sighting means in azimuth and is also operable to move the sighting means in elevation. In addition, the supporting means is mounted for vertical adjustment with respect to the casing in order that the sighting means may be adjusted to the height of the operator.

The mechanism in the casing is so arranged that the supporting means or mount for the sighting means rotates with the casing when the azimuth transmitter is actuated by its manual means which also rotates the casing, and so that the supporting means rotates with respect to the casing when the searcher mechanism is actuating the azimuth transmitter, the casing then remaining stationary. The supporting means is actuated in elevation in response to either the operation of the elevation transmitter by its manual means or by the searcher mechanism. This arrangement provides for always maintaining the sighting means pointed in the same direction as the light beam since it is always moved in accordance with the movements of the searchlight.

The supporting means or binocular mounting as it may be termed, is so designed that the least amount of effort on the part of the operator is required to follow the binocular during a searching or scanning operation. The binoculars are supported at the end of an arm which is pivotally secured to a second arm which is supported by a vertically disposed and adjustable element rotatably mounted on the casing. The second or rigid arm is disposed at an angle to both the vertical and horizontal planes through the top of the vertical member so that the supporting arms are located to the side of the operator and the binoculars positioned over the center of the casing.

Referring now to the drawings in which like parts in the different figures are designated by the same reference characters, Fig. 1 is a perspective view showing the general nature of the comparator controller unit comprising generally a tripod 10 having a base 11 upon which the casing or box 12 is rotatably mounted and the binocular mount 13 which is rotatably mounted on the casing. This view shows the azimuth side of the comparator and shows various elements which will be referred to hereinafter.

Fig. 2 is a detailed view of the comparator mechanism and the binocular mounting. The azimuth and elevation remote control transmitters 14 and 15 are supported within the casing as shown in Fig. 1.

In this embodiment of the invention provision is made for actuating the transmitters 14 and 15 both independently by manual means and collectively by a searcher or scanning mechanism shown generally at 16 and which will be described in detail hereinafter. As shown the azimuth transmitter 14 may be driven by either one or both of two shafts 17 and 18 which are connected to the movable element of the transmitter through a differential gear 19 and gears 20 and 21. The drive shaft 17 may be manually actuated by either one of two hand wheels 21 and 22 both of which drive the shaft through a slip clutch 23. As shown the hand wheel 21 is geared directly to the shaft 24. The hand wheel 22 is connected to shaft 24 through a combination clutch and gear reducer 25 controlled by the

handle 26. When the handle 26 is in position shown, the gear reducer is effective and shaft 24 is actuated at some speed less than that of the hand wheel. With the handle in the opposite position, the clutch 21 is engaged to connect the hand wheel directly to the shaft 24 to provide a one to one speed ratio.

Provision may be made to disengage gears 20 and 30, as shown in Fig. 15, in order to disconnect the transmitter 14 from the driving mechanism when desired. The transmitter 14 may be disconnected by sliding either one of the gears 20 and 30 along its shaft and in this instance a shift lever 42 is utilized for this purpose. Since it may be desirable in many cases to maintain the rotor of the transmitter in the same position after being disconnected in order that it may be reconnected to the drive mechanism in the same relative positions, provision is made for locking the rotor by means of a suitable brake 49. In this instance the brake 49 is stationarily mounted and engages the gear 30 when it is shifted out of engagement with the drive gear 20. Any other suitable arrangement may be used so long as it locks the rotor of the transmitter. A similar arrangement for disconnecting and locking the transmitter 15 is provided.

As will be described more fully hereinafter, the azimuth transmitter 14 functions to operate a receiver at the searchlight or other controlled object. Under such conditions, it is desirable to limit the maximum speed of the transmitter to a point at which the transmitter and receiver or repeater will remain in synchronous or operative relation. In order to accomplish this function provision is made for rendering the hand wheels 21 and 22 ineffective, by a forced operation of the slip clutch 23, when a predetermined maximum speed is reached. As shown, the slip clutch 23 is geared to and drives a speed-responsive braking device 28, the details of which are shown in Figs. 10 and 11, although any other suitable device may be used for this purpose.

The brake device comprises a cylindrical casing 29 for housing the rotating element 31 which is driven by a shaft 32 geared to the slip clutch as shown in Fig. 2. The rotating element 31 comprises a disc 33 on which is pivotally mounted a pair of brake shoes 34 and 35, which are normally retained in a non-braking position by the springs 36 and 37, connected between the opposite ends of the yokes 38 and 39. It is apparent that when the rotating element 31 attains a predetermined speed in either direction of rotation, the brake shoes 34 and 35 are forced outwardly into engagement with the casing 29 which functions as a brake drum. The shoes are connected by a link 41 rotatably mounted on the shaft 32, which functions to cause the shoes to move together. When the brake functions at a predetermined speed, the slip clutch 23 is loaded to such an extent as to cause it to slip and render the hand wheels temporarily ineffective to further increase the speed of the transmitter to a point where the remote control, of which the transmitter 14 is a part, would be pulled out of synchronism or otherwise rendered ineffective or inaccurate.

The details of the slip clutch 23 are shown in Fig. 8. The driven shaft 24 is secured to a sleeve 43 which is secured to the clutch plate 44. The casing 45 is secured to the driving shaft 17 and encloses the stationary friction element 46 and the spring actuated element 47 between which the plate 44 is clamped. As will be readily

understood, when the load on shaft 17 exceeds a predetermined value, the plate 44 will slip between the elements 46 and 47. The load at which the device starts to function may be varied by means of the adjusting screws 48 which vary the spring tension.

In order to rotate the casing 12 in azimuth in accordance with the movements of the azimuth transmitter 14, a stationary gear ring 51 is provided on the base 11 of the tripod 10 which engages a drive pinion 52 actuated through a differential gear 53 from the ring gear element of the differential 19 as shown. Since the ring gear element is driven directly by the manual drive shaft 17 the rotation of the casing occurs in accordance therewith. It will be observed however that rotation of the searcher shaft 18 does not rotate the casing since it is connected with one of the sun-gears of the differential 19 and has no effect upon the ring gear.

The ring gear element of differential 53 is locked by a worm 54 on the shaft 55 which may be rotated by the knob 56 in order to shift the position of the casing 12 relative to the position of the object controlled by the transmitter 14. Such might become desirable when tracking an aircraft while observing it through the binoculars in order to shift azimuth position of the binoculars with respect to the searchlight beam.

In this embodiment, the operation of the hand wheels 21 and 22 to drive shaft 17 also actuates the azimuth dial 51, which indicates the position in azimuth of the searchlight, through the worm 58, worm gear 59, slip clutch 61, and pinion 62 as best shown in Figs. 3 and 4. An adjusting knob 63 is connected to the dial shaft through shaft 64 and gears 65 which may be used to adjust the dial by slipping the clutch 61.

Referring now to the elevation control side of the comparator mechanism, it will be observed that it is generally similar to the azimuth control portion of the mechanism just described, the elevation transmitter 15 being actuated by the shafts 66 and 67 through a differential gear 68. Head wheels 71 and 72 drive the transmitter 15 through a slip clutch 73 which is controlled by a speed responsive brake 74. The hand wheel 72 is connected to shaft 66 through a combination clutch and speed reducer 75, as before. The elevation dial 76, not shown in this figure, is actuated directly from the ring gear element of the differential 68 through a similar gear arrangement and slip clutch as in the case of the azimuth dial 51. An adjusting knob 70 is also provided, as shown, which performs the same function as the knob 63.

As will be described more in detail hereinafter, the binocular mount 13 is rotatably mounted on the casing 12 in order that the binoculars 17 or other sighting means, may be moved relative to the casing in azimuth. The mount is so designed that it is operable to move the binoculars in elevation.

The elevational movements of the mount 13 are effected in accordance with the operation of the elevation transmitter 15 and, in this instance, these movements are produced through a gear mechanism comprising gears 78 and 79, differential 81, shaft 82, spur gears 83 and 84, bevel gears 85, which drive a shaft 86 which is geared to the elevation control shaft 87 of the mount through the spur gears 88 and 89. Therefore, it is apparent that the elevation operations of the binocular mount are effected, regardless of whether the transmitter 15 is being driven by

the hand wheels 71 and 72 or by the searcher mechanism 16 through the shaft 67.

The planetary element of the differential 81 is connected to a worm wheel 80 by means of a hollow shaft extension 80 through which the shaft 82 extends. A worm 97 engages worm wheel 80 in order to hold the planetary element against rotation so that the shaft 82 may be driven through the differential 81.

10 In order to provide for shifting the elevational position of the binoculars with respect to the elevational position of the light beam the worm 97 is connected to an adjusting knob 100 by means of a shaft 120, bevel gears 131 and shaft 132.

15 The movements of the binocular mount 13 in azimuth are effected in two ways, by the movement of the casing 12 and by the movement of the mount 13 relative to the casing. When the azimuth transmitter 14 is being driven by the hand wheels 21 and 22, such as when tracking an aircraft or in following the sound locator, it is desirable to rotate the casing in accordance with the movement of the light beam in azimuth.

25 This movement of the casing is therefore utilized to move the binocular mount 13. When, however, it is desired to effect a searching operation about a predicted location of an aircraft, it is desirable to rotate the binocular mount 13 relative to the casing 12. In this instance, the mount 13 is rotated relative to the casing by gearing it to the searcher shaft 18 as shown through the worm 91 and worm gear 92 which actuate shaft 93 on which is mounted a spur gear 94 that engages a gear segment 95 of an arm 96 connected to the rotatable elements of the mount, as will be described hereinafter. Thus, it is seen that the binocular mount 13 is geared directly to the searcher shaft 18 and is actuated 35 in azimuth with respect to the casing only when the searcher mechanism 16 is operated.

40 When the hand wheels 21 and 22 are actuated, however, the binocular mount 13 is held stationary with respect to the casing 12, since the searcher shaft 18 is then stationary and the mount 13 rendered ineffective to rotate it by the worm and worm gear connection, just described.

45 Before describing the binocular mount further, a description of the searcher or scanning mechanism 16 will now be set forth in connection with Figs. 2, 3, 4, 5, and 6.

50 The purpose of the searcher mechanism, which may be referred to as a mechanical searcher in this instance, is to provide for collectively actuating the azimuth and elevation transmitters 14 and 15 in a predetermined coordinated manner such as to cause, in this case, the searchlight to be moved in such a way as to cause the beam to systematically scan or travel over a predetermined area in the sky and to completely cover the area to be searched without appreciable overlap in order to scan the maximum area in the shortest possible time.

55 Due to the nature of the comparator controller, the conditions under which it is used, and the minimum weight requirements, the searcher mechanism must be of rugged and simple construction, light in weight, compact in arrangement and smooth and as near frictionless as possible in operation. In order to meet all of these requirements in a satisfactory manner, a mechanism, which is best illustrated in Fig. 5, is utilized to drive the azimuth and elevation searcher shafts 18 and 67. The mechanism, in general, comprises a linkage 98 and a variable-

ratio gear mechanism 99 for actuating the linkage which in turn drives the searcher shafts 18 and 67.

60 The linkage comprises four separate links two of which 101 and 102 are pivotally mounted to oscillate about a common axis 103, as shown, and which may be termed the drive links since they carry gear segments 104 and 105 which mesh with pinions 106 and 107, respectively, which are secured to the drive gears 108 and 109. The drive gears are connected to the searcher shafts 18 and 67 by means of the pinions 110 and 111 in such manner that the motions of the drive links 101 and 102, cause the transmitters to be rotated.

65 The other two links 112 and 113 which may be termed the actuating links, are pivotally connected to the movable ends of the drive links and are both connected with a stub shaft 114 as shown in Fig. 6, the link 113 being rotatably mounted on the stub shaft and the link 112 being secured or keyed thereto.

70 The variable-ratio gear mechanism 99 which is utilized in this instance to actuate the linkage 98 comprises a compound gear 115 having offset portions 116 and 117 which cooperate with a compound pinion 118 comprising a circular spur gear element 119 and an eccentric spur gear 121 mounted on a shaft 122 which is journaled in a box type link 123 pivotally secured 75 to a stub shaft 124 on the compound gear 115, as shown.

75 The stub shaft 114 to which the drive link 112 is keyed is journaled in suitable bearings 125 in the box link 123 and is connected to the shaft 35 122 carried by the link through spur gears 126 and 127 keyed or otherwise secured to their respective shafts.

80 As will be readily understood when the compound gear 115 is rotated by the shaft 128, which ever one of the elements of the compound pinion 118 which is in engagement with the compound gear 115 is caused to crawl around this gear since it is held against rotation by the link 112, which is keyed to shaft 114. This causes the box link 45 123 to be revolved about its pivot connection 124 on the gear 115 carrying the linkage 98 with it.

85 The element 116 of gear 115 has a constant or fixed radius whereas the other element 117 has a varying radius, as shown, in order to obtain a 50 spiral movement of the searchlight beam. In this embodiment, the ratio between the gear element 116 and pinion 119 is 4 to 1, while that of the gear element 117 and eccentric pinion 121 is one to one when in the center position, as 55 shown in Fig. 5, and which, of course, increases until at the transfer points 129 and 131 the ratios are the same. In order that predetermined cycles of elevation and azimuth movements may be obtained, it is necessary that the pinion 119 make a 60 predetermined number of complete revolutions for each revolution made by the compound gear 115. In other words, the transfer points on gear 115 are fixed.

90 In this instance, it was found desirable to increase the overall ratio of the variable ratio gear 99 above that which could be obtained by the compound gear 115 and pinion 118 alone. This may be done by means of the spur gears 126 and 127 having a ratio of three to one, which in this particular embodiment, gives the variable ratio gear 99 a ratio of approximately 6 to 1.

95 As shown in Fig. 6, the center line of the stub shaft 114 is offset with respect to the axis of shaft 128 or compound gear element 115 which 75

causes the spiral movement to begin as soon as the mechanism starts to function.

In this embodiment of the invention, provision is made for actuating the searcher mechanism 16 manually or by power by means of a hand wheel 137 and motor 138, or both may be used simultaneously.

As shown in Figs. 2 and 9, the shaft 128 on which the variable ratio gear wheel 115 is mounted is driven by a gear train comprising gear wheels 139, 141, 142 and 143. The gear wheel 143 is secured to the ring gear element of a differential gear mechanism 144, one side of which is driven by means of a worm wheel 145 actuated by the worm 146, which may be turned by the hand wheel 137 located on top of the casing 12 as shown in Fig. 3. The true position of the worm 146 is as shown in Fig. 3, but it is shown on the opposite side of the worm wheel 145 in Fig. 2 in order to more clearly illustrate its function.

The other side of the differential 144 is driven by shaft 147 which may be connected through a clutch 148 to a gear mechanism 149 driven by the searcher motor 138 supported on the outside of the casing 12, as shown in Fig. 1.

As will be readily understood, the motor 138 may be operated at different speeds in accordance with the speed desired for searching. The searcher mechanism 16 may be actuated by either the motor 138 or hand wheel 137 separately or simultaneously as desired. The hand wheel control may be actuated at any time to modify the action of the searcher mechanism 16 when under power operation.

With reference to Fig. 2, it will be observed that a pointer 151 is geared to the drive shaft 128 which may cooperate with a suitable stationary index to provide a continuous indication of the position of the searcher mechanism and thereby the position or point on the scanning path or cycle at which a beam is or will be directed. The pointer revolves in a glass covered chamber 152 on the top of the casing 12 in view of the operators.

In order to provide for causing the binocular or other sighting means to always be pointed in the direction of the searchlight beam or toward the predicted position of the aircraft, as determined by the sound locator, a binocular mount 13, as shown in Figs. 2, 12, 13 and 14, is utilized. Since the mechanism for actuating the azimuth and elevation transmitters 14 and 15 is such as to effect rotation of the casing 12 when the azimuth transmitter is separately actuated by the hand wheels 21 and 22, the position in azimuth of the binocular may be maintained under such conditions by causing the mount 13 to be moved by the movements of the casing 12. However, when the mechanical searcher 16 is in operation, the casing 12 remains stationary which requires that the mount 13 be moved in azimuth relative to the casing. The movements in elevation of the binocular must be obtained under both conditions by actuation of the mount 13 since the casing has no elevational movement.

In order to produce these functions, the mount 13 is so constituted that it operates automatically in the desired manner in response to the hand wheel and searcher operations.

As shown, the binocular 17 is supported at the end of the elevation arm 154 which is rotatably secured to and supported by a second arm 155 which is rotatably mounted on the casing 12.

The rotatable mounting or support for the arms 154 and 155 is best shown in Fig. 14. The arm 155 is removably secured to a head 156 which

is keyed or otherwise secured to the upper end of a threaded tube 157 which engages a nut 158 for the purpose of adjusting the height of the mount as will be described more in detail hereinafter. The nut 158 is supported by means of a sleeve 159 which is rotatably mounted on bearings 161 and 162 within the stationary sleeve 163, secured to the top of the casing 12. The rotatably mounted sleeve 159 is secured against rotation relative to the threaded tube shaft 157 by means of a key 164 which engages a longitudinal keyway in the tube shaft thereby permitting the binocular mount to be adjusted vertically with respect to the casing and to rotate thereon through the functioning of the sleeve 159.

The rotation of the binocular mount 13 with respect to the casing 12 is effected by rotating the sleeve 159 by means of the arm 96 as referred to hereinbefore and shown in Fig. 2. Rotation of the searcher shaft 18 drives the arm 96 through the gear connection shown and previously described. Since the shaft 18 is stationary when the manual drive shaft 17 is actuated, the gear connection then functions to hold the mount stationary with respect to the casing 12.

The elevational movements of the supporting arm 154 are effected by the vertically mounted drive shaft 87 rotatably supported by the threaded sleeve 157 by bearings 165 and 166 and which drives a second shaft 167, journaled in the azimuth arm 155, by means of bearings 168 and 169, through the bevel gears 171 and 172 and slip clutch 173. A worm gear 189 is keyed to the shaft 188 of the elevation arm 154 and meshes with a worm 178 on the opposite end of the shaft 167. The vertical shaft 87 is driven in accordance with the movements of the elevation transmitter 15 as described hereinbefore. The bevel gear 172 is connected to the shaft 167 by the slip clutch 173 in order to prevent any damage to the mechanism should the elevation arm 154 be moved too far in either direction.

The adjusting nut 158 may be actuated by a bevel gear wheel 174 rotatably mounted on the stationary sleeve 163 and provided with an operating handle 175. Since the nut 158 is carried by the sleeve 159 which rotates with the threaded tube 157, it will also rotate with the tube when the binocular mount is rotated which will prevent any change in the vertical position of the mount except when the bevel gear is actuated.

In order that the binocular mount 13 may be readily removed from the casing 12, it is removably secured to the head 156 of the rotating element by means of the thumb nuts 176 and 177 as shown.

It will be observed that the relative positions of the arms 154 and 155 are such as to position the binoculars or sighting means in line with the vertical support and to enable the observer to utilize the binoculars without interference from the mount. The arm 155 is preferably inclined upwardly at a slight angle, as shown in Fig. 12, and is also disposed at a side angle, as shown in Fig. 13, of such magnitude as to so position the gear box 178 that it will not interfere with the observer.

Due to the fact that the binocular is mounted on the arm 154, it moves vertically in an arc having a comparatively large radius which readily permits the observer to easily maintain his eyes in the proper position with a minimum amount of head movement.

The binocular is supported on the arm 154 by means of a bracket 179 which also functions as

a sighting device. The bracket 179 is rotatably mounted upon an arm 181 which in turn is rotatably secured to the arm 154, in order that the binocular and sight may be moved in azimuth and elevation relative to the arm 154. The arm 181 is releasably secured to the arm 154, by means of a centering segment 182 and thumb nut 183. As shown best in Fig. 12, a similar device, comprising a segment 184 and thumb nut 185, is utilized to control the movement of the bracket on the arm 181. The binoculars may be clamped to the bracket by means of clamping device 186.

In order to compensate for the weight of the binoculars and bracket on the arm 154 and thus balance the mount for movement in either direction, a coil spring 187 is interposed between the shaft 188 or worm gear 189 and the gear box 178 on arm 155, of such strength as to practically balance the torque tending to rotate the arm 154 in a counter-clockwise direction. This reduces the load on the searcher mechanism and the actuating elements of the mount to a minimum and makes for greater accuracy and freedom of operation.

There is also provided in the comparator casing 12, as shown in Figs. 3 and 4, azimuth and elevation receivers 191 and 192 for driving the inner dials 193 and 194 which cooperate with the outer dials 57 and 76 to indicate the relative positions in azimuth and elevation of the sound locator and searchlight. The receivers 191 and 192 are disposed within the casing as shown in Figs. 3 and 4, and in this instance the dials are mounted directly on the shafts of the receivers. The azimuth dial arrangement is shown in Fig. 1, the elevation dials 76 and 194 being on the opposite side of the casing 12.

Having now described the details of construction of the comparator, reference should be had to Fig. 15 which is a simple diagrammatic showing of a sound-locator remote control system for searchlights and other movable objects which are to be directed from a remote position. In this view, only those elements necessary to illustrate the functioning of the comparator have been illustrated and are designated by the same reference numerals as used in the other figures.

The searchlight 197 may be of the usual construction having a drum 198 rotatably mounted on trunnions 199 supported on a rotatable sub-base 201 which is rotatably mounted on a main or stationary base 202. The movements of the drum in elevation are effected by suitable receiver 203, while the rotation of the drum and sub-base 201 may be controlled by a receiver 204, both of which are electrically connected to the transmitters 14 and 15 in the comparator. Any suitable remote control or follow-up system may be utilized to control the movements of the searchlight from the comparator; however, in this instance, a schematic showing of the remote control system as disclosed in my copending application, Serial No. 21,010, filed May 11, 1935, has been made. The transmitters 14 and 15 and their respective receivers 204 and 203 are in the form of synchro-machines and constitute synchro-ties. The movements of the searchlight are effected by means of power units (not shown) mounted in the sub-base 201 and controlled by the receivers 203 and 204. The transmitters and receivers, however, may take any other desired form, such, for example, as step-by-step motors, etc.

The sound locator 205 is of well known construction and requires no detailed description.

Its movements in azimuth and elevation in following a sound source are transmitted to the comparator by means of transmitters 206 and 207, which are also synchro-machines electrically connected to the receivers 191 and 192 in the comparator to form synchro-ties and thus actuate the inner dials 193 and 194 in accordance with the movements of the sound locator.

As will be readily understood, separate movements in azimuth and elevation of the searchlight may be effected by operating the transmitters 14 and 15 by means of the hand wheels 22 and 72. Since these movements are indicated by the azimuth and elevation dials or indicators 57 and 76 on the comparator, the searchlight may be caused to follow the movements of the sound locator indicated by the dials 193 and 194, thereby causing the searchlight to track or follow the sound source as its position is predicted by the sound locator 205.

During these operations, the binocular mount 13 is actuated as described hereinbefore in order to maintain the binoculars 77 or other sighting means carried by the mount to follow the movements of the searchlight.

In the event that the sound source is not in the light beam of the searchlight when it is turned on, and a scanning or searching operation is required to locate it the mechanical searcher 16 is set in operation in order to produce the desired coordinated operations of the transmitters 14 and 15, to cause the beam to travel over a predetermined area in a systematic manner as described hereinbefore. In this instance, the binocular mount 13 is actuated in unison with the transmitters in order to cause the sighting means to follow the beam as it traverses the area to be scanned.

It may be stated, in conclusion, that while the illustrated embodiment constitutes a practical embodiment of my invention, I do not wish to limit myself strictly to the exact details herein illustrated, since modifications of the same may be made without departing from the spirit of the invention, as defined in the appended claims.

I claim as my invention:

1. In combination, a searchlight having a drum mounted for movement in azimuth and elevation, electro-responsive means operable to actuate the drum in azimuth and elevation, position control transmitters for controlling said electro-responsive means, a casing for said transmitters, means on the casing for supporting and moving a pair of binoculars in azimuth and elevation relative to the casing, and mechanical means operable to collectively actuate the position control transmitters in accordance with predetermined operating cycles and the binocular supporting means in accordance therewith independently of the casing, thereby to effect predetermined co-ordinated movements of the searchlight drum and the binoculars while the casing remains stationary.

2. The combination with an object mounted for movement in azimuth and elevation and power means including azimuth and elevation receivers for actuating the object, of a controller comprising azimuth and elevation position transmitters, a rotatably mounted casing for said transmitters, manually-operable means for simultaneously actuating the azimuth transmitter and rotating the casing, manually operable means for actuating the elevation transmitter independently of the casing, and additional means operable to simultaneously actuate both transmitters in a predetermined co-ordinated manner without

effecting a movement of the casing to effect predetermined movements of the object in azimuth and elevation.

3. In a comparator controller for controlling the movements of an object in azimuth and elevation, azimuth and elevation control transmitters, driving means for the transmitters including a pair of drive shafts having a gear wheel positioned on one end of each shaft and a pair of actuating levers pivotally mounted at a common point having gear segments thereon to engage the gear wheels on the drive shafts, a variable ratio gear mechanism having a driving crank for operating the driving means, and links connecting the actuating levers to the crank, thereby to produce predetermined coordinated movements in azimuth and elevation of the transmitters and a corresponding movement of the object being controlled.

20 4. In a comparator control device, a pair of electro-responsive position transmitters for controlling the movements in azimuth and elevation of a movable object, manually-operable means for actuating each transmitter independently of the other, means including a linkage mounted for oscillatory movement about a fixed pivotal support, for actuating both transmitters simultaneously, a variable ratio gear mechanism having a driving crank connected to said linkage for actuating said linkage in a predetermined manner about the fixed pivotal support to effect predetermined coordinated movements of the transmitters and thereby cause the movable object to follow said coordinated movements, and means for actuating said variable ratio gear mechanism.

45 5. In a comparator control device, a pair of electrical position transmitters for controlling the movements in azimuth and elevation of a movable object, manually-operable means for actuating each transmitter independently of the other, means including a pivotally-mounted linkage for actuating both transmitters simultaneously, a variable ratio gear mechanism for actuating the linkage to operate the transmitters in a predetermined coordinated manner, whereby the movable object is caused to move in accordance with the resultant movements of the transmitters, a motor, a handwheel, and a differential gear device connecting the motor and handwheel to the variable ratio gear mechanism, whereby either or both may be utilized to drive the said mechanism.

55 6. In a comparator controller for controlling the movements of a movable object in azimuth and elevation, in combination, azimuth and elevation directing transmitters manually-operable means for actuating each transmitter independently of the other, means including a pair of levers pivotally mounted at a common fixed point for actuating the transmitters independently of the manual means, drive means including a variable ratio gear mechanism for actuating said levers to produce coordinated movements of the transmitters, and consequently the object, a motor for driving said drive means, manual means for actuating said drive means and means whereby either the motor or manual means may be utilized separately or together to actuate the drive means.

70 7. In a comparator, in combination, a rotatably mounted casing, a pair of transmitters in the casing, means whereby said transmitters may be independently actuated, means whereby said transmitters may be operated collectively, a binocular

mounting rotatably supported by the casing, and means whereby the binocular mounting is actuated in one predetermined manner and the casing rotated when the transmitters are individually actuated and in another predetermined manner with the casing stationary when they are actuated collectively.

75 8. A comparator unit comprising a rotatably-mounted casing, a pair of electro-magnetic transmitters in said casing, means mounted on the casing for supporting a binocular, said means being movable with respect to the casing in azimuth and elevation and movable with the casing in azimuth, means whereby the transmitters may be actuated individually or collectively in accordance with a predetermined cycle of operation, means responsive to the individual operations of the transmitters for rotating the casing and actuating the binocular supporting means in elevation, and means responsive to the collective operation of the transmitters for actuating the binocular mounting means in both azimuth and elevation in accordance with the predetermined operating cycle of the transmitters.

9. A comparator controller comprising, a casing member, means for supporting the casing, means for supporting and pointing a binocular comprising a first support member rotatably mounted on top of the casing and adjustably mounted for vertical movement with respect thereto, a second support member pivotally secured to the end of the first member for movement in a vertical plane for supporting the binocular, and means for actuating the first and second support members to effect movements of the binocular in a predetermined manner.

10. A comparator controller comprising a casing member, means for supporting the casing, means for supporting and pointing a sighting device comprising a first support member rotatably mounted on the casing and adjustably mounted for vertical movement with respect thereto, a second support member pivotally secured to the end of the first member for supporting a sighting device, said second support member being movable with respect to the first in a vertical plane, means for effecting rotational movement of the first support member to position the sighting device in azimuth, and means for actuating the second support member to position the sighting device in elevation.

11. In a comparator controller, in combination, an apparatus casing, sighting means, means mounted on said casing for supporting the sighting means, said supporting means comprising a first element rotatably supported by the casing and adjustably mounted for vertical movement with respect thereto and a second element pivotally secured to the first and movable relative thereto in a vertical plane, means for rotating the rotatably mounted first element, means for actuating the second element, and means for adjusting the position of said element vertically in order to vary the height of the sighting means above the casing.

12. In a comparator control device, in combination, a pair of electro-magnetic transmitters having rotatable elements, manually-operable variable-speed means associated with each transmitter for separately actuating the rotatable elements of the transmitters at will, each of said variable speed means including a differential gear device, a rotatably mounted casing for housing said transmitters and actuating means, means

75

- including a second differential gear device driven from one of said variable speed means through its associated differential gear means whereby the casing is rotated in accordance with the operation of the rotatable element of one of the transmitters, and means for controlling the ring gear element of the said second differential gear for adjusting at will the azimuth position of the casing with respect to the position of the rotatable element of said transmitter.
13. In a comparator unit, in combination, a rotatably mounted casing, a pair of transmitters in said casing, a binocular mount rotatably mounted on the casing and operable to move the binoculars supported thereby in both azimuth and elevation independently of the casing, said binocular mount comprising a vertical shaft rotatably mounted on the casing, a transversely extending arm detachably mounted on the upper end of said shaft and movable therewith and a second arm pivotally mounted on the outer end of the transversely extending arm for carrying the binocular and movable in a vertical plane, means operable to simultaneously drive the transmitters through predetermined cycles of movements, and means actuated thereby to simultaneously rotate the vertical shaft and actuate the second arm of the binocular mount in elevation in accordance with the movements of the transmitters while the casing remains stationary.
14. In a comparator unit, in combination, a rotatably mounted casing, a pair of transmitters in said casing, a binocular mount comprising a support member rotatably mounted on the casing and a binocular supporting arm pivotally mounted on the support member for elevational movements in a vertical plane operable to move the binoculars supported thereby in both azimuth and elevation independently of the movements of the casing, means operable to simultaneously drive the transmitters through predetermined cycles of movements, means actuated in accordance with the movements of one of the transmitters during its cycle of movement for effecting rotational movement of the support member of the binocular mount relative to the casing in accordance with said cycle, and means actuated in accordance with the movements of the other transmitter during its cycle of movement for effecting elevational movements of the binocular supporting arm of the binocular mount in accordance with said cycle.
15. In a comparator control unit for controlling the movements of a searchlight in azimuth and elevation, in combination, a rotatably mounted casing, elevation and azimuth control transmitters in said casing, a binocular mounting sighting device rotatably mounted on said casing, said device comprising a support member rotatably mounted on the casing and an arm for supporting the binocular pivotally mounted on said support member for movement in a vertical plane operable to move the binocular in azimuth and elevation relative to the casing and also in azimuth in accordance with the rotational movement of the casing, manually-operable means for actuating the elevation transmitter and the binocular supporting arm of the binocular mounting device in unison, manually-operable means for actuating the azimuth transmitter and casing in unison, and additional means for effecting a co-ordinated operation of both transmitters and similar co-ordinated movements of the support member and the binocular supporting arm of the binocular mounting device independently of the casing.

JOHN F. PETERS.
